CLAIM

I claim the ornamental design for a paver restraint, as shown and described.

DESCRIPTION

A holding device for paving blocks to minimize movement of the paving blocks.

FIG. 1 is a pictorial view of a paver restraint in accordance with the present invention;

FIG. 2 is a top view of the paver restraint as shown in FIG. 1;
FIG. 3 is a side elevation view of the paver restraint of FIG. 1 taken from the left hand side of the paver restraint as shown in FIG. 1;

FIG. 4 is an end elevation view of the paver restraint of FIG. 1 taken from the lower end of the paver restraint as shown in FIG. 1; and,

FIG. 5 is an end elevation view of the paver restraint of FIG. 1 taken from the upper end of the paver restraint as shown in FIG. 1.

The paver restraint is shown in the drawings as broken on the web to indicate indefinite length.
